UNITED STATES PATENT OFFICE.

HUGH P. QUIN, OF WASHINGTON, GEORGIA.

DESIGN FOR A BACK-BAND HOOK.

SPECIFICATION forming part of Design No. 30,096, dated January 31, 1899.

Application filed January 5, 1899. Serial No. 701,267. Term of patent 7 years.

To all whom it may concern:

Be it known that I, HUGH P. QUIN, a citizen of the United States, residing at Washington, in the county of Wilkes and State of Georgia, have invented and produced a new and original Design for a Back-Band Hook, of which the following is a full, clear, and exact description.

Reference is to be had to the accompanying drawings, forming a part of this specification, in which—

Figure 1 is a face view of the back-band hook embodying the features of my design. Fig. 2 is a rear view of the same, and Fig. 3 is a cross-section on the line 3 3 of Fig. 1.

My design consists in its entirety in the configuration of the back-band hook A, whose upper end B is broad and flaring and whose lower part C extends from such flaring part B. Near the lower end of the part C there appears an aperture D, and a hook emanates from the lower edge of such aperture and is curved upwardly and inwardly, the tip

E of said hook terminating within the aperture D. 25

The leading feature of my design consists in the back-band hook, whose upper end is flaring and wide and in whose lower end appears an aperture and a hook adjacent said aperture and curving upwardly and toward 30 the latter.

Another feature of my design consists in the three-cornered shield-shaped opening F, appearing in the upper portion B, and a series of three apertures G, one of which appears 35 adjacent each corner of the opening F, and a fourth aperture appearing below the aforesaid apertures and in alinement with the lowest one of the latter.

What I claim is—

The design for a back-band hook, as herein shown and described. 40

HUGH P. QUIN.
